UNITED STATES PATENT OFFICE

156,545

PIE RACK

Howard R. Lewis, Chicago, Ill.

Application July 1, 1948, Serial No. 147,318

Term of patent 3½ years

(Cl. D44—1)

To all whom it may concern:

Be it known that I, Howard R. Lewis, residing in the city of Chicago, county of Cook, State of Illinois, have invented a new, original, and ornamental Design for a Pie Rack, of which the following is a specification, reference being had to the accompanying drawing, forming a part thereof, in which:

Fig. 1 is a perspective view of a pie rack showing my new design;

Fig. 2 is a top view; and

Fig. 3 is a cross-sectional view.

I claim:

The ornamental design for a pie rack, substantially as shown.

HOWARD R. LEWIS.
